RICHARD C. HARRINGTON, OF NEWARK, NEW JERSEY.

Letters Patent No. 78,962, dated June 16, 1868.

IMPROVEMENT IN DOOR-LOCKS.

The Schedule referred to in these Letters Patent and making part of the same.

TO ALL WHOM IT MAY CONCERN:

Be it known that I, RICHARD C. HARRINGTON, of Newark, in the county of Essex, and State of New Jersey, have invented a new and improved Door-Lock; and I do hereby declare that the following is a full, clear, and exact description thereof, which will enable others skilled in the art to make and use the same, reference being had to the accompanying drawings, forming part of this specification, in which—

Figure 1 represents an outside view of my improved lock, the outside plate having been removed.

Figure 2 is a detail outside view of the same, the parts being in a position different from that shown in fig. 1.

Figure 3 is a vertical cross-section of the same, the plane of section being indicated by the line *xx*, fig. 1.

Similar letters of reference indicate like parts.

This invention relates to a new door-lock, which is so arranged as to be altogether burglar-proof. It is provided with two key-holes, one on the inside and one on the outside, but not opposite to each other, and it is so constructed that it can at all times be locked and unlocked from the inside, also unlocked from the outside when it has been locked from the outside, but it cannot, under any circumstances, be opened from the outside if it has been locked from the inside; and as provision is also made that the lock cannot be picked from the outside, it will be fully burglar-proof when locked from the inside.

A represents the case of the lock, in which *a* is the inside plate and *b* the outside plate.

The case is longer than it is high, and is divided by a vertical partition, *c*, into two compartments *B* and *C*.

To the compartment *B*, which is nearest to the outer edge of the lock, leads a key-hole, *d*, from the inside of the door, while from the outside a key-hole is made into the plate *b*, communicating with the compartment *C*.

D is the bolt, which reaches through the partition *c* into the compartment *C*, and which is provided with two recesses for the key, one over each one of the key-holes.

E is the tumbler, which is pivoted in the compartment *C*, and which reaches through a slot in the partition *c* into the compartment *B*. It has a lug or pin, *e*, which holds and prevents the bolt from moving in or out, when the same is locked or unlocked, as its fits over a similar lug or pin, *i*, which is secured to the bolt. From the outside the bolt is simply locked or unlocked by inserting the key and letting it raise the tumbler, so that it can push the bolt either in or out as the case may be. A curtain, *F*, may also be arranged in the compartment *C*, or any other arrangements made therein, by which the locks are now generally protected, or with which they may be advantageously provided.

The key-hole *C*, in the inside plate of the lock-case, is surrounded by a curvilinear curtain or slotted cam, *G*, which is pivoted at its lower end, and which is shaped as is clearly shown in figs. 1 and 2.

H is a sliding plate, which is guided between two guides, *f f*, and which is pressed by the outer end of a spring, *h*, upon the upper end of the cam *G*. A lug, *g*, upon this plate, fits through a slot in the bolt *D*, that slot having a small downward extension, as shown. The outer end of the tumbler *E* rests upon the sliding plate *H*.

The operation is simple, and as follows: When the bolt is to be unlocked from the inside, the key moves the cam *G* towards the partition *c*, raises the plate *H*, and with it the tumbler *E*, so as to release the pins, *e i*, and then moves the bolt back. The cam *G* and plate *H*, as well as the tumbler *E*, will then be in the same position which is shown in fig. 1, although the bolt will be drawn in.

When, then, the bolt is locked from the outside, the key will simply raise the tumbler and push out the bolt. Then all the parts are in the position shown in fig. 1. But if the bolt is to be locked from the inside, then the key moves the cam towards the face of the lock, thereby the plate *H* is raised on the rounded upper end of the cam, the plate *H* raising also the tumbler, and then the bolt is pushed out.

But as soon as that is done, the plate *H* is, by the spring *h*, moved down into a depression of the cam, so that its lug, *g*, falls into the small downward extension of the slot in the bolt, said downward extension being completely, or nearly so, filled by the said lug, as shown in fig. 2. It will now be understood that the bolt cannot be moved unless it is released from the lug *g*, which cannot be done from the outside, that is, from the compartment *C*, as for that purpose the plate *H* must be raised, which can only be done by means of the cam *G*.

The partition *c* prevents that the plate *G* can be raised by any article that may be inserted through the outer key-hole.

The improvements herein described can be applied to locks of different kinds of construction.

What I claim as new, and desire to secure by Letters Patent, is—

The cam *G*, sliding plate *H*, and lug *g*, in combination with the bolt *D*, tumbler *E*, and the partition *c*, all made and operating substantially as and for the purpose herein shown and described.

RICH'D C. HARRINGTON.
